CIRCUIT MAKER AND BREAKER

Mervin Rehrer, Pine Grove, Pa.

Application October 6, 1939, Serial No. 298,333

2 Claims. (Cl. 200—157)

The present invention relates to improvements in circuit makers and breakers, and more particularly to manually controlled switches.

Oftentimes, a person who has retired to bed desires to listen to the radio, or read by an electric light, in order to relax so as to more easily go to sleep. In the ordinary course of events, however, the person becomes so drowsy as to fall asleep without disconnecting the appliance; or if 10 the person is able to switch off the electric current, the effort required usually is sufficient to cause the user of the appliance to become thoroughly awakened.

It is an object of the invention to provide a 15 control device for an electrical appliance, such as a radio, heating pad, or electric light, and which will disconnect the electrical appliance when the user goes to sleep.

Another object of the invention is to provide 20 a circuit maker and breaker which is controlled by the tension and relaxation of the grip of the operator.

A further object of the invention is to provide 25 a switch having shielded contacts not liable to become entangled in or dislocated by bed clothing or the like.

A still further object is to provide a switch 30 having smooth exterior surfaces and of a generally flat contour not liable to injure a person resting thereon or otherwise in contact therewith.

Other objects and advantages of the invention 35 will become apparent from the following detailed description, taken in connection with the accompanying drawing, forming a part of this specification and in which drawing:

Figure 1 is a view, partly in section and partly 40 in elevation, of the circuit maker and breaker and showing its connection to a power supply line, the switch being open.

Figure 2 is a top plan view of the circuit maker 45 and breaker, the switch being closed.

Figure 3 is an end elevation of the circuit 50 maker and breaker.

In the drawing, which shows only a preferred 55 embodiment of the invention, and wherein similar reference characters denote corresponding parts thruout the several views, 10 designates the switch, in the form of a handle, and including a pair of levers 11 having inner or adjacent sides 12 forming dihedral angles defined by the faces 13—14. Embedded flush with the faces 13 and secured by screws 15 are the butts 16 of a suitable hinge 17 having its pin 18 coextensive with 50 the edges of the dihedral angles formed by the

intersecting faces 13—14. Suitable means may be provided to urge the faces 14 apart. In the present instance, the faces are provided with pockets 19 in which are disposed the opposite end portions of an expansion coil spring 20. 5 Suitable means may also be provided to hold the faces 14 in adjacent spaced relation. As shown, a pair of headed pins 21 may be mounted in the ends 22 of the levers, one of the pins pivotally supporting an arm 23 terminating at its free end 10 in a hook 24 adapted to engage the other pin 21.

Formed in the faces 14 are sockets 25 one carrying 15 at its base portion an insulative plate 26 supporting a spring contact 27. The other socket 25 carries an insulative block 28 having a skirt 29 extending into the opposite socket, and enclosing a contact 30 adapted to engage and disengage the contact 27 upon pivotal movement of the levers 11. It will be noted that the arrangement 20 of the angularly disposed faces 13—14 is such as to limit rocking movement of the levers 11 in either direction, and that the lower end of the skirt 29 is disposed within the confines of the socket 25 carrying the contact 27 when the contacts 25 are disengaged, as well as when they are engaged.

Extending thru longitudinal passageways 31 are insulated conductors 32 secured at their ends 33 to the contacts 27 and 30. These conductors 30 32, at their opposite ends 34, may be connected to a current conducting cord 35 in any desired manner. In the example shown, a plug 36 is employed to form a connecting member. Projecting from the plug 36 is a pair of prongs 37 for insertion into a conventional electric outlet (not shown). Within the body of the plug are terminals 38—39 of the prongs 37 and a third insulatively supported terminal 40. To the terminals 38 and 40 may be connected the ends 34 of the 40 conductors 32, the ends 41 of the conducting cord 35 being connected to the terminals 39 and 40.

Upon grasping the levers 11 and applying a tension sufficient to overcome the resistance of the spring 20, the contacts 27 and 30 will be 45 brought into engagement so as to permit current flow thru the cord 35. Upon relaxation of the grip of the person holding the switch, the spring 20 will cause the levers 11 to pivot about the hinge pin 18 so as to disengage the contacts and 50 discontinue the flow of current in the cord 35.

It will therefore be readily seen that a device 55 has been provided which will automatically disconnect the flow of current to an electrical appliance upon the falling asleep of a user, due to

the natural relaxation of the hand grip of the sleeping person.

Various changes may be made to the form of invention herein shown and described, without departing from the spirit of the invention, or the scope of the following claims.

I claim:

1. In a grip controlled switch, a pair of similarly shaped levers having adjacent sides, said sides each forming a dihedral angle, means securing said levers for rocking movement with the edge of one dihedral angle substantially co-extensive with the edge of the other dihedral angle, said sides each having a socket, a contact mounted in the base of a given one of said sockets, a projection mounted in the remaining socket and having a free end disposed in said given socket, and a second contact carried by said free end, said contacts being movable between positions of engagement and disengagement upon rocking movement of said levers, and said projection hav-

ing its free end movable between positions within the confines of said given socket.

2. In a grip controlled switch, a pair of similarly shaped levers having adjacent sides each forming a dihedral angle, means securing said levers for rocking movement with the edge of one dihedral angle substantially co-extensive with the edge of the other dihedral angle, said sides each having a socket, a contact mounted in the base of a given one of said sockets, a projection mounted in the remaining socket and having a free end disposed in said given socket, said free end being provided with a recess, and a second contact carried by the free end within the recess, said contacts being movable between positions of engagement and disengagement upon rocking movement of said levers, and said projection having its free end movable between spaced positions within the confines of said given socket.

MERVIN REHRER.
